(57) **CLAIM**

The ornamental design for a display screen with a graphical user interface, as shown and described.

DESCRIPTION

FIG. 1 is a front view of a display screen with a graphical user interface showing the new design.

The broken lines in the FIGURE, both the broken lines of the border showing the remainder of the display screen and the icons in broken lines, illustrate unclaimed environment and form no part of the claimed design.

1 Claim, 1 Drawing Sheet
